(57) **CLAIM**

The ornamental design for a data processing device as shown and described.

DESCRIPTION

FIG. 1 is a perspective view of a data processing device in accordance with our design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof;

FIG. 7 is a bottom plan view thereof;

FIG. 8 is an enlarged detail view taken from area '8' in FIG. 1; and,

FIG. 9 is an enlarged detail view taken from area '9' in FIG. 2.

The even-dash broken lines represent portions of the data processing device that form no part of the claimed design. The dash-dot broken lines represent the extents of the detail views and form no part thereof.
